APPLICATOR FOR INSERTING NATURAL HAIR UNDER A WIG

Bruce B. Althoff, 7322 SW. 80th St. Plaza,
Miami, Fla.

Filed Aug. 6, 1970, Ser. No. 24,358

Term of patent 14 years

Int. Cl. D28—03

U.S. Cl. D86—10

FIG. 2

FIG. 1 is a perspective front view of an applicator for inserting natural hair under a wig, showing my new design.

FIG. 2 is a perspective rear view thereof.

I claim:

The ornamental design for an applicator for inserting natural hair under a wig, substantially as shown.
